UNITED STATES PATENT OFFICE.

MAX HOFFMANN, OF BERLIN, GERMANY, ASSIGNOR TO PAUL MEYER AKTIEN-GESELLSCHAFT, OF BERLIN, GERMANY.

LEVER-CONTROLLED SWITCH.

No. 918,854.

Specification of Letters Patent.

Patented April 20, 1909.

Application filed February 2, 1907. Serial No. 355,344.

To all whom it may concern:

Be it known that I, MAX HOFFMANN, a citizen of the Empire of Germany, residing at Berlin, in the Empire of Germany, have 5 invented a new and useful Lever-Controlled Switch, of which the following is a specification.

In electric switches and cut-outs it is very desirable that the pressure for pressing 10 brushes on contact pieces or terminals be not exerted direct by the operator, the more so if a heavy current is to pass through the brush. In such cases hitherto toggle levers were mostly employed, which permit to 15 move quickly the brush so long as it does not offer any resistance, and to produce at the last moment a strong pressure on the brush with a small exertion by the operator, so that the brush may be distorted and thoroughly 20 pressed on the terminals. However the toggle levers present the defect, that the varying speed, with which the brush is moved, being a sine function can not be determined at will.

25 My invention relates to a new kind of lever-controlled switches, whereby the advantage is obtained, that the speed of the brush during its operation can be determined at will, it being made large during 30 that part of the path, during which no pressure needs be exerted on the brush, and the said speed being made to considerably decrease from the moment, at which the distortion of the brush commences, so that the 35 speed is minimal at the moment, at which the maximum pressure is produced with a small exertion by the operator.

The chief feature of the new lever-controlled switch is a cam, which is pivotally 40 connected with the lever.

I will now proceed to describe my invention with reference to the accompanying drawing, in which—

Figure 1 is an elevation of a lever-controlled switch, in which a single support is 45 provided for the parts, Fig. 2 is similar to Fig. 1 but modified in that two supports are provided for the parts and that the operating lever is forked, Fig. 3 is a horizontal section 50 through the broken line A—B in Fig. 2, and Fig. 4 is an elevation of the forked lever and two cams. Fig. 5 is a vertical sectional view of the switch in its open position. Fig. 6 is

an end elevation of the same looking from the left in Fig. 5.

55

Similar characters of reference refer to similar parts throughout the several views.

Fig. 1 shows a lever-controlled switch with a single support and a movable cam. 1 denotes a suitable base plate of insulating material, on which two terminals 2 and 3 are fastened. The latter may be connected with the respective circuit or conductors (not shown) in any known manner and are to be connected with one another at will by means 60 of a yielding brush 5. The one terminal 3 is shown as made in one piece with a vertical support 4^a, on which preferably three pins 6^a, 7^a and 8^a are provided. On the pin 6^a a lever 9 and a cam 10 are mounted to rock independently of each other. The lever 9 is provided with a handle 11 of insulating material. On the pin 7^a a lever 12 is mounted to rock, which between its two ends is provided with a roller 13 on a pin 14. The free 70 end of the lever 12 is pivotally connected with the brush 5, which may be of any known construction. The free end of the lever 12 is connected with a pin 15 on the lever 9 by means of a helical spring 16. The pin 8^a 80 serves as a stop for the cam 10. The latter is provided with two teeth 17 and 18, on either of which the pin 15 on the lever 9 can act. The cam 10 is adapted to work with the roller 13 on the lever 12 and is at the 85 most distant point from the pin 6 provided with a shallow recess 19, in which the roller 13 can engage. For the position shown of the several parts the tension of the helical spring 16 may be made moderate.

90

This lever-controlled switch is operated as follows: In the position of the several parts shown in Fig. 1 the two terminals 2 and 3 are electrically connected by means of the yielding brush 5. For disconnecting the two terminals 2 and 3 from each other the handle 11 is seized by the operator and moved from right to left. During this motion the pin 15 can freely move in the space between the two teeth 18 and 17, so that the helical spring 16 100 will be stretched by means of the pin 15 and the operator needs only to strain this spring up to the maximum of its tension at the moment that the pin 15 strikes the tooth 17. The operator in further turning the handle 11 105 will have to exert a certain force for shifting

the cam 10 while slightly depressing the roller 13 and the lever 12. From an examination of the figure it will be clear, that only the friction produced by the maximum pressure between the roller 13 and the cam 10 needs to be overcome for shifting the cam 10 by means of the handle 11. When at last the farthest point of the cam 10 leaves the roller 13, the latter under the action of the maximum pressure of the spring 16 will roll on the cam 10 toward the pin 6^a and thus turn the cam 10 in a direction opposite to that of the hands of a clock, so that the strained helical spring 16 will be released and will violently turn the lever 12 upward and thus suddenly detach the brush 5 from the two terminals 2 and 3. The tooth 18 of the cam 10 may then strike the pin 15, whereby the turn of the cam 10 is limited. As the cam 10 is not balanced, of course it will turn back and rest on the roller 13. The pin 8^a serving as a stop may limit the turn of the lever 9 from right to left. Henceforward the several parts may occupy a position, which is determined by the tension of the helical spring 16, the lever 9 resting with its pin 15 on the tooth 18 of the cam 10 and the cam 10 in turn resting on the roller 13, while the two levers 9 and 12 are drawn together by means of the helical spring 16. Thus the brush 5 is kept detached from the two terminals 2 and 3 by means of the helical spring 16.

For switching on the brush 5 the handle 11 is seized by the operator and is turned downward from left to right. During this motion the pin 15 on the lever 9 will bear against the tooth 18 of the cam 10 and will thereby turn the latter, so that the cam 10 will depress the roller 13 and the lever 12 and thus lower the brush 5, while a little stretching the helical spring 16. The moment that the brush 5 comes in contact with the two terminals 2 and 3, the pin 15 on the lever 9 will by the tooth 18 of the cam 10 act upon the latter for further depressing the roller 13 and therewith the lever 12 and the brush 5 while further stretching the helical spring 16. The brush 5 will therefore be distorted until the roller 13 engages in the shallow-recess 19 of the cam 10, when the brush 5 will be tightly pressed on the two terminals 2 and 3 with the maximum pressure. It will be seen, that the operator is thus enabled to turn quickly the handle 11 and that his power is better utilized than hitherto for producing the maximum pressure on the brush 5.

Obviously the shape of the cam 10 may be varied to suit the requirements of the operator.

The lever-controlled switch may be varied in many respects without departing from the spirit of my invention. For example two parallel supports 4, 4, see Figs. 2 and 3, may be provided, between which the parts 6, 7, 8, 9, 10, 12 and 13 may be located. The lever

12 may consist of two side parts between which the roller 13 is placed, as is shown at Figs. 2 and 3. The lever 9 may be forked, see the part 9' in Figs. 2 and 4 and there may be two separate cams 10, 10.

70

I claim:

1. In a lever-controlled switch, the combination with two terminals, of a support, a lever pivoted in said support, a flexible brush pivotally connected with said lever and adapted to be pressed on said two terminals for closing the circuit, a pivot in said support, an operating lever mounted to rock on said pivot, a cam mounted to rock on said pivot and adapted to press on said lever for pressing on said brush, means for transmitting the motion from said operating lever to said cam for operating and releasing same, and a helical spring connecting said lever with said operating lever for suddenly detaching said brush from said two terminals.

80

2. In a lever-controlled switch, the combination with two terminals, of a support, a lever pivoted in said support, a flexible brush pivotally connected with said lever and adapted to be pressed on said two terminals for closing the circuit, a pivot in said support, an operating lever mounted to rock on said pivot and provided with a pin, a cam mounted to rock on said pivot and adapted to press on said lever for pressing on said brush, said cam being provided with two teeth either of which the pin on said operating lever can strike for turning the cam in the respective direction, and a helical spring connecting said lever with the pin of said operating lever and adapted to suddenly detach said brush from said two terminals on said cam being released.

90

3. In a lever-controlled switch, the combination with two terminals, of a support, a lever pivoted in said support and provided with a projection, a flexible brush pivotally connected with said lever and adapted to be pressed on said two terminals for closing the circuit, a pivot in said support, a cam mounted to rock on said pivot and adapted to slide over the projection of said lever and thereby to press said brush on said two terminals, it having two teeth and on its point farthest from said pivot a shallow recess for engagement with said projection, an operating lever mounted to rock on said pivot and provided with a pin adapted to strike either tooth of said cam and to thereby turn the latter in the respective direction, and a helical spring connecting said lever with the pin on said operating lever, the two teeth on said cam leaving a certain amount of play to the pin on said operating lever so that the latter for breaking the circuit is permitted to strain said helical spring up to the maximum of its tension before it strikes one tooth and thereby shifts said cam out of engagement with the projection on said lever, whereupon

100

110

115

120

125

130

the strained spring suddenly detaches said brush from said two terminals.

4. In a lever-controlled switch, the combination with two terminals, of a support, a lever pivoted in said support and provided with a roller, a flexible brush pivotally connected with said lever and adapted to be pressed on said two terminals for closing the circuit, a pivot in said support, an operating lever mounted to rock on said pivot, a cam mounted to rock on said pivot and adapted to press on the roller on said lever for pressing on said brush, means for transmitting the motion from said operating lever 10 to said cam for operating and releasing same, and a helical spring connecting said lever with said operating lever for suddenly detaching said brush from said two terminals.
- 20 5. In a lever-controlled switch, the combination with two terminals, of a support, a lever pivoted in said support and provided with a roller, a flexible brush pivotally connected with said lever and adapted to be 25 pressed on said two terminals for closing the circuit, a pivot in said support, an operating lever mounted to rock on said pivot and provided with a pin, a cam mounted to rock on said pivot and adapted to press on the roller 30 on said lever for pressing on said brush, said cam being provided with two teeth either of which the pin on said operating lever can strike for turning the cam in the respective direction, and a helical spring connecting 35 said lever with said operating lever and

adapted to suddenly detach said brush from said two terminals on said cam being released.

6. In a lever-controlled switch, the combination with two terminals, of a support, a lever pivoted in said support, a roller on said lever, a flexible brush pivotally connected with said lever and adapted to be pressed on said two terminals for closing the circuit, a pivot in said support, a cam mounted to 40 rock on said pivot and adapted to slide over said roller for pressing said lever on said brush, it having two teeth and on its point farthest from said pivot a shallow recess for engagement with said roller, an operating 45 lever mounted to rock on said pivot and provided with a pin adapted to strike either tooth of said cam and to thereby turn the latter in the respective direction, and a helical spring connecting said lever with the pin 50 on said operating lever, the two teeth on said cam leaving a certain amount of play to the pin on said operating lever so that the latter for breaking the circuit is permitted to strain said helical spring up to the maximum of its 55 tension before it strikes one tooth and thereby shifts said cam out of engagement with said roller, whereupon the strained spring suddenly detaches said brush from said two terminals.

MAX HOFFMANN.
